H. DeWitt Goodwin

UNITED STATES PATENT OFFICE.

ANTHONY L. CRESCI, OF VINELAND, NEW JERSEY.

DOOR-OPERATING MECHANISM.

1,371,074.

Specification of Letters Patent. Patented Mar. 8, 1921.

Application filed December 18, 1918. Serial No. 267,255.

To all whom it may concern:

Be it known that I, ANTHONY L. CRESCI, a citizen of the United States, residing at Vineland, in the county of Cumberland and 5 State of New Jersey, have invented certain new and useful Improvements in Door-Operating Mechanism, of which the following is a specification.

My invention relates to improvements in 10 door operating mechanism, particularly adapted for garage doors. The object of my invention is to operate the door by an electric motor and to provide a switch for controlling the motor to open and close the 15 door; a further object of my invention is to provide switches for stopping the motor automatically when the door reaches the open or closed position; a still further object of my invention is to provide a cushioning device for stopping the door without shock or jar after the motor is stopped, and a still further object of my invention is 20 to provide a safety device for supporting the door in case the supporting cable should break.

Referring to the accompanying drawings; Figure 1, is a view in elevation showing a door and the door frame or guides and showing my invention embodied therein; 30 Fig. 2, is a perspective view of a switch and the means for operating the same; and Fig. 3, is a vertical section on line 3—3, Fig. 1.

In the accompanying drawings, in which 35 like reference characters refer to like parts, 1 represents a door mounted in vertical guides 2 and 3 in which the door slides vertically. The door is operated by an electric motor 5 adapted to rotate in either direction. A shaft 6 is driven by the motor through gear wheels 7 and 8, the belt 9 and belt pulley 10 secured to said shaft 6 or by any other suitable means. A flexible member 12, in the form of a sprocket chain 40 or cable, is secured to the door 1 and to a counter-weight 14, the flexible member 12 passing over a sheave 15 and a pulley 16. The sheave 15 is driven by the shaft 6 through a friction clutch 18 interposed between the shaft 6 and the sheave 15. Said 45 clutch 18 is adjusted so as to exert only sufficient friction to move the door when the door is properly counter-balanced and to slip in case the motor is not stopped at

the time the door is acted upon by the cushioning device.

The motor 5 is controlled by a hand switch 20, which may be located in any part of the building. The hand switch 20 controls two electric circuits for operating the 60 motor 5 in different directions, to raise or lower the door. Said electric circuits are shown diagrammatically in the drawings. Each electric circuit from the hand switch 20 includes a switch operated automatically 65 by the door, which latter is provided with a cam 22 for engaging the switch arms.

The said automatically operated switches 80 and 31 are similar in construction, each comprising a knife switch 34, inclosed in a casing 35 which is secured in a fixed position to the guide frame 2, or other stationary member. The pivoted knife 36 is moved by a connecting rod 37 attached to a lever 40 pivoted at one end in a fixed bearing 41. The free end of the lever 40 projects into the path of the cam 22 carried by the door. Said lever 40 is shaped in the form of a right angle so that the knife switches may be located upon the 85 side of the guide frame 2 opposite to the door. The lever 40 moves in a guide member 43 provided with a stop pin 44 against which the lever 40 is moved, by the action of a spring 45, when the arm 40 is free 90 from the cam 22 upon the door. Said lever 40 is also provided at its free end with a roller 46 which readily rides over the cam 22, which latter moves the lever 40 into the position in which the switch 31, 95 Fig. 1, is shown, in which position the knife 36 has been moved and broken the circuit between the switch contact plates 38 and 39. The switch 30 in Fig. 1 and also in Fig. 3 is shown in the closed position 100 with the knife 36 closing the circuit between the contact plates 38 and 39.

In Fig. 1, the hand switch 20 is shown in the position to operate the motor 5 in a direction to lower the door 1, and the door 100 is shown in the lower or closed position, in which position the cam 22 has shifted the switch 31 into the open position, broken the circuit and stopped the motor; the hand lever 21 still remaining in its original position to close the circuit through conductors A and B which circuit includes the switch 31.

By reversing the hand switch 20, the opposite circuit will be completed through conductors A and C, including switch 30 which is in the closed position, and the 5 motor will be operated in the direction to raise the door. When the cam 22 engages the lever 40 of the switch 30, said switch will be opened and stop the motor. The other switch 31 will be closed by the spring 10 45 as soon as the door moves the cam 22 away from the lever 40, of said switch 31; thus the opposite circuit is closed, at the switch 31, but still remains broken at the hand switch 20. The switch 20 can again 15 start the motor through either circuit which includes an automatic switch in the closed position.

The cushioning device for stopping the door without any jar, consists of the cylinder 50 secured in a fixed position. A piston head 51 is mounted in the cylinder 50 and is operated by a rod 52 secured thereto. Said rod 52 is slidably mounted at its opposite end in a bracket 54 secured to the top 25 floor 55 of the building. Upon the rod 52 are secured stops 56 and 57 which are engaged by a bracket 59 carried by the door. Immediately before the door reaches the limit of its movement, in either direction, 30 the bracket 59 on the door, by coming in contact with the stops 56 or 57 will move the rod sufficiently to force the piston 51 against the air in the cylinder 50. The air exhausts slowly through the valves 60 and 35 retards the movement of the door. Said rod 52 is provided with a counterbalance-weight 61 which balances the weight of the rod and prevents the piston 51 from moving in the cylinder due to the weight of the rod.

40 The flexible member 12 is connected to the door through a head 63, slidably mounted in a bracket 64. The head 63 carries the arm 65 of a pawl 66 pivoted on the pin 67 secured upon the door. The free end of the 45 pawl 66 is located adjacent to a toothed rack 68 secured to the door frame 3, so that if the flexible member 12 should break, the arm 65 will be released and the spring 69, attached to said arm, will cause the pawl to 50 engage the rack and thus prevent the door from falling.

My invention is shown herewith in connection with a door but it may also be applied to elevators, dumb waiters and hoisting apparatus.

Having thus described my invention I claim and desire to secure by Letters Patent:

1. In a door, or the like, a frame in which the door is slidably mounted, an electric 60 motor for moving the door, an electric circuit to operate the motor, a switch in the electric circuit secured upon said frame, an arm pivotally mounted upon said frame adjacent to said switch, a casing inclosing said 65 switch, a connecting rod between the arm

and the switch extending into said casing, and a cam to operate said arm when the door is in a position to bring the cam and the arm into engagement and thereby break the circuit and stop the motor.

2. In a door, or the like, a frame in which the door is slidably mounted, an electric motor for moving the door, an electric circuit to operate the motor, a switch connected in said circuit, said switch secured upon said frame, a cam upon the door, an L-shaped arm extending into the path of the cam, a bearing upon the frame in which said arm is pivotally mounted, a connecting rod between the arm and said switch, a roller upon the free end of the arm adapted to be engaged by the said cam and move said arm, and a spring for moving the said arm in the opposite direction when not engaged by the cam.

3. In a door, or the like, a frame in which the door is slidably mounted, an electric motor for moving the door, an electric circuit to operate the motor, a knife switch connected in said circuit, said switch secured upon said frame, an arm, a bearing upon the frame in which the arm is pivoted, a connecting rod between the arm and the knife switch, a U-shaped plate secured upon the frame for guiding the arm, a spring to move the arm and close the switch, and a cam upon the door adapted to move the arm against the action of said spring and open the switch.

4. In a door, or the like, an electric motor for operating the door, electric circuits for operating the motor, switches located in the said circuits, a double faced cam upon the door for actuating either switch when the door is in either extreme position, a cylinder 100 forming a compression chamber, a piston in said cylinder, a counter-balance weight attached to said piston, and means actuated by the door for moving the piston in relation to the cylinder when either of said switches is 105 thrown out to stop the motor.

5. In a door, or the like, a bracket secured to the door, a movable head in said bracket, a flexible member connected with the head for lifting the door, a pawl pivoted upon the door, a rack secured in a fixed position 115 adapted to be engaged by the pawl, and an arm upon the pawl engaged by the said head for holding the pawl out of action when the door is supported by the flexible member.

6. In a door, or the like, operating means, a friction clutch driven by the said operating means, a sheave driven by the clutch, a flexible member driven by the sheave, a counter-balance weight secured to the flexible member, a head attached to the flexible member, a bracket upon the door in which said head is movably mounted, a pawl controlled by said head for stopping the door when released from the flexible member, a 130

cylinder secured in a fixed position, a piston in said cylinder, means upon the door for moving the piston against the pressure in said cylinder, and a counter-balance-weight attached to said piston.

7. In a door, or the like, a frame in which the door is slidably mounted, a pawl pivoted upon the door adapted to engage the said frame and hold the door in relation to the frame, a flexible member connected with the

pawl for moving the door and for holding the pawl out of engagement with the frame, and a bracket upon the door to limit the movement of the pawl by said member.

In testimony whereof I affix my signature 15 in the presence of two witnesses.

ANTHONY L. CRESCI.
